UNITED STATES PATENT OFFICE.

SAMUEL J. JOHNSTON, OF LEESBURG, VIRGINIA.

SASH-FASTENER.

SPECIFICATION forming part of Letters Patent No. 652,782, dated July 3, 1900.

Application filed September 1, 1899. Serial No. 729,203. (No model.)

To all whom it may concern:

Be it known that I, SAMUEL J. JOHNSTON, a citizen of the United States, residing at Leesburg, in the county of Loudoun and State 5 of Virginia, have invented a new and useful Sash-Fastener, of which the following is a specification.

This invention relates to sash-fasteners or sash-locks which are associated with a sliding sash and window-frame to provide means for locking the sash against movement in either direction at any desired point.

The object of the invention is to provide a simple, cheap, easily-manipulated, and reliable device of this character having positive means for securely locking the sash against movement either upward or downward after having been raised or lowered to the desired position.

With this end in view the invention primarily contemplates a sash-fastener having a minimum number of operating parts which are so constructed and arranged as to occupy little space and at the same time can be readily fitted to any window without marring or defacing the same.

A further object of the invention is to construct the fastener in such a way as to permit of its easy manipulation, while at the same 30 time providing an effective lock that will always be reliable in action and cannot become easily disarranged.

With these and other objects in view, which will more readily appear as the nature of the 35 invention is better understood, the same consists in the novel construction, combination, and arrangement of parts hereinafter more fully described, illustrated, and claimed.

The essential features of the invention are 40 necessarily susceptible to some modifications without departing from the spirit or scope thereof, but the preferred embodiment of the improvements is shown in the accompanying drawings, in which—

Figure 1 is a perspective view of a portion of a window-frame and its sash equipped with the sash fastener or lock embodying the improvements contemplated by the present invention. Fig. 2 is a detail in perspective of the lock proper removed from the window-frame. Fig. 3 is a longitudinal sectional view of the construction shown in Fig.

2. Fig. 4 is a detail in perspective of the lock-wheel, comprising the revoluble pinion and bolt-engaged disk. 55

Like numerals of reference designate corresponding parts in the several figures of the drawings.

The invention forming the subject-matter of the present application embraces two principal parts—namely, a rack-bar and a lock proper—which are respectively fitted to the contiguous portions of the sliding sash and window-frame, and while the rack could be applied to the window-frame and the lock to 60 the sash, and vice versa, still in the preferred application of the invention it has been found most practicable to apply the rack or rack-bar to one of the stiles of the sliding sash, so that the lock proper will always be in a fixed position 65 convenient for manipulation irrespective of the elevation of the sash.

Referring particularly to the drawings, the numeral 1 designates a straight rack-bar provided with a plurality of perforated ears 2, 75 arranged at suitable points and adapted to receive screws or equivalent fasteners 3 for securing the rack-bar to one of the stiles of the sliding sash 4 contiguous to one of the sides or stiles of the window-frame. The said 80 rack-bar 1 preferably extends the full width of the sash to which it is fitted, so that the latter may be held locked at any point to which it is capable of being raised or lowered, and associated with this rack-bar is the lock 85 proper, which is supported on the side of the window-frame adjacent to the stile of the sash to which the rack-bar is fitted.

Referring more particularly to the lock proper of the device, the working parts of 90 this lock are held within a bracket 6. This bracket 6 is formed with a securing-plate having terminal ears 7, receiving screws 8 or equivalent fasteners for holding the bracket to the window-frame, and the said bracket 95 also has offset therefrom an open frame 9, within which is loosely mounted the revoluble lock-wheel 10. The spindle or axle extremities 12 of this lock-wheel are journaled in opposite sides of the bracket 6 to provide 100 for permitting the wheel to freely rotate within the open frame of the bracket and also project out of the frame, so as to engage with the teeth of the rack-bar 1.

The revoluble lock-wheel essentially comprises a pinion 13 and a bolt-engaged disk 14, projected from one side thereof, preferably in the form of an integral hub extension, and 5 the said pinion 13 of the wheel, as well as the rack-bar 1, are sufficiently wide to maintain a proper mesh, so as to insure the easy raising and lowering of the sash. The bolt-engaged disk 14, offset from one side of the 10 pinion 13, is provided in the periphery thereof with a plurality of sockets or notches 15, adapted to receive therein one end of the sliding lock-bolt 16. The sliding lock-bolt 16 reciprocates in a plane entirely at one side of 15 the pinion 13 of the lock-wheel, while the stem of said bolt 16 works through a casing 17, formed at one end of the bracket 6, and below which easing the lower end of the bolt-stem has fitted thereto a finger-plate 18, which 20 is of a sufficient size to be readily grasped between the thumb and first finger to provide for the retraction of the bolt from the socket 15 with which it may be engaged.

To provide for the normal engagement of 25 the sliding bolt 16 with one of the notches 15, a spring 19 is housed within the casing 17 and is arranged to exert an upward pressure against the bolt 16 to secure the desired result.

30 In the use of the fastener to provide for raising or lowering the sash to any desired point it is simply necessary to grasp the finger-plate 18 and retract the bolt from the notch of the disk 14, so as to release the lock-wheel and permit it to freely rotate as the 35 sash is moved up or down, and when the sash has about reached the desired point the finger-pressure on the sliding bolt may be relieved, so that the upper end thereof will ride 40 on the periphery of the disk 14 and automatically spring into engagement with the next socket or notch 15. When the bolt is thus engaged with the socket or notch 15, the lock-wheel is held against rotation, so as to positively 45 lock the sash against movement in either direction.

By reference to Fig. 3 of the drawings it will be seen that I have provided a novel form of casing for inclosing the spring of the 50 sliding bolt and for supporting the revoluble pinion and lock-wheel in a manner to expose the latter, so that it may engage with the rack and also present the notched disk in a position for engagement by the bolt.

55 This casing includes a vertical plate, a bracket offset from the plate, and a boxing which is integral with the plate and is disposed in the vertical plane of the bracket, the vertical wall of the bracket being extended to form one of the walls of the boxing. 60 This boxing is provided in its top and bottom with openings of different sizes, the

top opening being square in shape. The 65 sliding bolt is also square, so as to fit in and be guided by the square opening of the boxing, and this plate has the reduced stem, which is extended through the opening in the bottom of the boxing. The coiled spring 19 is housed entirely within the boxing, so as to be protected thereby against injury and an 70 accumulation of dust, one end of said spring being seated against a collar or washer on the bolt, while its opposite end bears upon the bottom of the boxing.

One of the important features of my invention 75 is the employment of an angular plate as the finger-piece 18, said plate being made fast, with the lower extremity of the stem forming a part of the bolt. The inner straight edge of this plate engages with the 80 lower part of the vertical plate 7, so as to slide against the same in the vertical travel of the bolt, while the other edge of the plate is extended or prolonged beyond the vertical bracket, thus exposing the plate always to 85 access for the operator to press against the same in retracting the latch from engagement with the lock-wheel preliminary to raising or lowering the sash. It is apparent that the 90 slideable locking element of my sash-fastener is guided at two points—first by the angular bolt sliding in the corresponding opening of the boxing and by the finger-plate riding against the vertical plate of the casing, whereby any tendency of the bolt to turn under 95 pressure of the finger applied against a corner of the plate is wholly overcome.

Having thus described the invention, what is claimed as new is—

In a sash-fastener, a casing comprising a 100 vertical plate, 7, a closed boxing, 17, having openings in the top and bottom, and an open bracket, 9, integral with the plate and said boxing, a slideable angular bolt, 16, having a stem and fitted slidably in the boxing, a 105 spring bearing against a shoulder of the bolt and housed within the boxing, and an angular finger-plate, 18, fast with the stem, below the boxing, and arranged for its inner edge to ride against the plate and for its 110 outer edge to project beyond the vertical plane of the boxing, combined with a rack, and a revoluble lock-wheel and pinion journaled in the bracket and plate for its notched disk to lie in the path of said bolt, substantially as described.

In testimony that I claim the foregoing as my own I have hereto affixed my signature in the presence of two witnesses.

SAMUEL J. JOHNSTON.
